UNITED STATES PATENT OFFICE

CARL STILL, OF RECKLINGHAUSEN, GERMANY.

APPARATUS FOR STIRRING AND MIXING LIQUIDS.

1,080,177.

Specification of Letters Patent.

Patented Dec. 2, 1913.

Application filed September 28, 1911. Serial No. 651,746.

To all whom it may concern:

Be it known that I, CARL STILL, a citizen of the German Empire, and residing at Recklinghausen, German Empire, have invented a certain new and useful Apparatus for Stirring and Mixing Liquids, of which the following is a description.

My invention relates to mixing apparatus or stirrers for liquids and in particular to such apparatus of the kind comprising a vertical tube open at its upper end and communicating at its lower end with a centrifugal device through which latter liquid, passed downward through the vertical tube, is expelled laterally or more or less radially. This apparatus is intended especially for mixing liquids of different specific gravity. For example, the apparatus is intended for use in connection with the purification of petroleum, coal-tar or the like by means of sulfuric acid, the object being to force the lighter petroleum or coal-tar down through the lower layer of sulfuric acid.

According to my invention the mixing or stirring apparatus is formed and operated in the manner of a centrifugal pump, for which purpose it terminates in a vane wheel *i. e.* it has a lower enlarged portion provided with a number of more or less radial blades; and it has an outlet opening extending completely around the periphery of the aforesaid enlarged part but interrupted or divided up into a number of separate openings by the said blades.

In order to render my invention easily intelligible reference is had to the accompanying sheet of drawing.

Figure 1 is a central vertical sectional view of the stirring apparatus assembled in the holder; Fig. 2 is a perspective view partly in vertical section of the stirrer, and Fig. 3 is a horizontal sectional view taken through the openings at the lower part of the stirrer.

a is an upright cylinder in the center of which is rotatably mounted the stirrer proper *c* secured to a vertical shaft *b*. The stirrer is, in the manner of a centrifugal pump, formed as a revolving body in such a manner that the paddles or blades *h* of the stirrer, with the series of discharge apertures between the lips or edges *c'* at the circum-

ference, extend into the bottom layer of specifically heavier liquid *d*, while the inlet *e* being in the shape of a tube arranged concentrically with the shaft, is extended upward considerably beyond the plane of separation *f* of the two liquids, but so that the mouth *g* is still covered with a sufficient layer of the upper liquid *k*. The inlet tube *e* is integral with the paddle body, and thus rotates with it. If the agitator is set in rapid rotation by any suitable means, as for example the gear *i*, it sucks the upper lighter liquid *k* through the central inlet tube *e*, and forces it, by the centrifugal action of the circulating apparatus, all along the periphery thereof, through the lower heavier liquid, with the result that, as the rotation continues, a vigorous continuous flow of the mixture of liquids is bound to take place, in a downward direction within the tube, and in an upward direction within the body of the mixing chamber. Such vertical flow downward and upward, in conjunction with the permanent eddying around the central shaft, causes a very energetic mixing of the two liquids, so that the desired result is attained within the shortest possible space of time.

As has already been proposed, the vertical shaft *b* is only supported at its upper end where it is mounted in a projection *l'* of the cover *l* of the apparatus, while the lower end with the circulating apparatus hangs freely in the liquid. This arrangement has the advantage that, by dispensing with any lower bearing, any damage thereto by the liquid at the bottom is avoided. This will be of especial advantage in cases where the metal of the trunnions and of the bearing parts is exposed to chemical attacks by the liquids employed; and the mode of construction described will be found always to be efficient and reliable. The bearing in the cover is sufficiently high above the surface of the liquid to prevent injurious attacks by stray particles of the liquid.

I claim as my invention:

A device for mixing two liquids of different specific gravity, including a container; a rotary element in the container, a stirrer secured to the lower end portion of the element and including a vertical hollow mem-

ber and a plurality of hollow horizontal radial blades which are secured to the lower end of said hollow member and which extend outwardly from the periphery thereof, said vertical hollow member being of a length which is considerably greater than the diameters of the blades and having its upper end open and disposed at a point sub-

stantially near the center of the height of the container to provide a liquid inlet.

In testimony whereof I affix my signature in the presence of two witnesses.

CARL STILL.
